UNITED STATES PATENT OFFICE.

LAWRENCE PAFF, OF BEAVER FALLS, PENNSYLVANIA.

DISPLAY-RACK FOR CARPETS, OIL-CLOTHS, &c.

SPECIFICATION forming part of Letters Patent No. 449,230, dated March 31, 1891.

Application filed June 25, 1890. Serial No. 356,682. (No model.)

To all whom it may concern:

Be it known that I, LAWRENCE PAFF, a citizen of the United States, residing at Beaver Falls, in the county of Beaver and State of Pennsylvania, have invented certain new and useful Improvements in Display-Racks for Carpets, Oil-Cloths, &c.; and I do hereby declare the following to be a full, clear, and exact description of the invention, such as will enable others skilled in the art to which it pertains to make and use the same, reference being had to the accompanying drawings, which form a part of this specification.

My invention relates to an improved carpet and oil-cloth display-rack; and it consists in certain details of construction and combination of parts, as will be fully set forth hereinafter.

In the accompanying drawings, Figure 1 is a front elevation of my improved rack partly in section, which is constructed in accordance with my invention. Fig. 2 is a plan view of the same, shown partly broken away. Fig. 3 is a face view of one of the forks used as a bearing for one end of a roll of carpet.

To put my invention into practice I provide two base-plates *a*, and attach thereto by means of screw-threads vertical tubes *b c*, arranged in a manner that the front set *c* are 30 farther apart than the rear set *b*. On the top of these tubes are placed two cross-bars *d*, connected together by a tube *e*. Secured a short distance above the base of these standards *b c* are two cross-pieces *f*, each of which may be adjusted vertically and held 35 rigidly in any desired position by means of set-screws *g*. I now provide a set of forks *h*, having an outwardly-projecting flange *i* and a short shaft *k*, with a means for connecting 40 an ordinary crank thereto. These forks *h* are adapted to be placed in the ends of a large roll of carpet and placed in the cross-pieces *f* in the rack. Adjustably secured to the two forward standards *c* of the rack by 45 means of set-screws *l* are brackets *m*, having hinged to each a bearing *n*, which are also provided with forks *o*, adapted to enter the ends of a roll of oil-cloth and be supported on the two brackets *m*. These bearings *n* are 50 provided with a slot *p* and a sliding plate *q*, actuated by a spring *r*, which when elevated

will permit the collar *s* on the fork-shaft *t* to enter and be confined therein when the said plate is lowered.

By means of this rack carpets, oil-cloths, &c., 55 may be easily displayed for sale, and readily rerolled.

Having thus described my invention, I claim—

1. The herein-described display-rack, consisting of the standards *b c* and base-plates *a*, the cross-bar *e* and top plates *d*, the bearings *f*, adjustably secured on the said standards and each having a fork *h* journaled therein, the adjustable brackets *m*, provided 60 with journaled forks *o*, and the lock-bearings *n*, substantially as set forth and described.

2. In a display-rack, the combination of two pairs of standards, the vertically-adjustable cross-pieces adapted to be rigidly clamped 70 thereto, and the rotatable forks loosely journaled in suitable bearings on said adjustable cross-pieces, substantially as described.

3. In a display-rack, the combination of the standards, the vertically-adjustable brackets 75 rigidly secured to said standards, the swiveled arms carried by said brackets, and the rotatable forks loosely journaled in the swiveled arms, substantially as described.

4. In a display-rack, the combination of the 80 standards, the supports rigid with said standards, the swiveled arms carried by said supports and provided with bearings, and the rotatable forks loosely journaled in said bearings and removably secured thereto, substantially as described.

5. In a display-rack, the combination of two pairs of upright standards, the vertically-adjustable supports *f*, rigidly clamped to said standards and carrying the rotatable forks, 90 and the brackets *m*, also clamped to the standards and having the swiveled bearings provided with rotatable forks *o*, substantially as described.

In testimony that I claim the foregoing I 95 hereunto affix my signature this 18th day of April, A. D. 1890.

LAWRENCE PAFF. [L. S.]

In presence of—

J. W. CARSON,
J. F. MERRIMAN.
